(57) **CLAIM**

The ornamental design for a coffee table, as shown and described.

DESCRIPTION

FIG. 1 is a top plan view of a coffee table showing my new and ornamental design.

FIG. 2 is an elevational right side view thereof, the opposite left side view being a mirror image.

FIG. 3 is a perspective right side view thereof,

FIG. 4 is a perspective left side view thereof,

FIG. 5 is an end view thereof, an opposite end view being a mirror image; and,

FIG. 6 is a bottom plan view thereof.

Features shown in broken lines in the drawings represent environment and form no part of the claimed coffee table.
